DRINKING GLASS COASTER

Herman B. Posmanter, 560 14th St., Oakland, Calif.

Filed July 23, 1965, Ser. No. 86,270

Term of patent 7 years

(Cl. D44—10)

FIG. 1

FIG. 2

FIG. 3

I claim:

The ornamental design for a drinking glass coaster, substantially as shown.
